UNITED STATES PATENT OFFICE.

CASPAR PRANGEMEIER, OF MÜNSTER, GERMANY.

COMBINED SPADE AND PICKAX.

SPECIFICATION forming part of Letters Patent No. 768,770, dated August 30, 1904.

Application filed April 6, 1903. Serial No. 151,421. (No model.)

To all whom it may concern:

Be it known that I, CASPAR PRANGEMEIER, engineer, a subject of the King of Prussia, Emperor of Germany, and a resident of Nos. 41 and 42 Katthagen, Münster, in the Empire of Germany, have invented a new and useful Combined Spade and Pickax, of which the following is a specification.

The present invention relates to an improved implement which can be used either as a spade or as a pickax for various purposes.

Special objects of the invention are to simplify and cheapen the construction and to render more efficient, serviceable, and durable in operation devices of the kind referred to.

With these ends in view the invention consists in the novel combination, arrangement, and adaptation of parts, all as more fully hereinafter explained, shown in the accompanying drawings, and then specifically set out in the appended claim.

As an example of carrying the invention into practice, Figure 1 of the drawings is a side elevation of the improved implement fixed as a pickax. Fig. 2 is a longitudinal section of the implement fixed as a spade, and Fig. 3 represents a perspective front elevation of the implement according to Fig. 1.

On the wooden shaft *a* is secured a metal tube *b*, which is provided at its front end with a transverse bore for the reception of a bolt *c*. The end of the metal tube *b* projecting beyond the shaft *a* is bifurcated and carries on a pin *f* rotatable the spade *d*. On the front end of the metal tube *b* a ring *e* is pushed, which, being previously provided with holes for the reception of the aforesaid pivot *f*, is retained in its place on the tube *b* by said pivot. The ring *e* shows a slot at its upper end running in the direction and terminating in the slot in the metal tube *b*. On the opposite lower side the ring *e* is completely split open. The head portion of the spade *d* is received in the upper slot of the ring *e* and rigidly secured therein, as will be more fully described later on, when the spade assumes the position illustrated in Figs. 1 and 3.

A guide-tube *g* is movably mounted on the metal tube *b*, which can be fixed in its work-

ing position by the hereinbefore-described bolt *c*. This bolt *c* is suitably secured to the guide-tube *g* by means of a short chain, and a screw-nut *h* may be screwed on the free end of the bolt *c*, if desired, in order to render impossible an accidental loosening of the parts. If a screw-nut *h* is employed, same may likewise be secured to the guide-tube *g* by means of a short chain. The bolt *c* can penetrate the tube *b* and shaft *a* either outside or through the guide-tube *g*. The end of the tube *b* projecting beyond the shaft *a* is provided with holes *i* for the reception of the bolt *k* in a direction corresponding to that of the pivot *f*.

For adjusting the implement as a spade the spade *d* is turned around its pivot *f* from the position shown in Figs. 1 and 3 to the position illustrated in Fig. 2. This movability of the spade *d* is rendered possible in view of the bifurcated front end of the metal tube *b* and by virtue of the lower slot of the ring *e*. Obviously the length of the slot originating the bifurcation of the metal tube *b* must be chosen, so as to enable the head portion of the spade *d* to take up room in the tube *b*. The bolt *k* is then pushed through the holes *i* in the tube *b* and through a bore previously provided at the proper place in the head portion of the spade *d*. By virtue of the two bolts *f* and *k* the spade *d* is rigidly secured in its position. The guide-tube *g* is then pushed along on the tube *b* until same can be secured in its working position by means of the bolt *c*, on the free end of which a screw-nut *h* may be screwed. The front edge of the guide-tube *g* is preferably thickened, so as to register with the marginal edge of the ring *e*.

To use the implement as a pickax, the bolt *c* is removed, the guide-tube *g* pushed backwardly, the bolt *k* removed, and thereupon the spade is turned to assume the position shown in Figs. 1 and 3. After fitting again the bolt *k* in the holes *i* and pushing the guide-tube *g* along the metal tube *b* until the bolt *c* can secure said guide-tube in its position the spade *d* will be rigidly secured, as the head portion of same is accommodated in the

upper slot of the ring *e* on the one hand and rests against the front edge of the guide-tube *g* on the other hand.

The head portion of the spade *d* can be shaped to serve as an ax, and the implement may likewise serve as a hoe for agricultural purposes.

What I claim as my invention, and desire to secure by Letters Patent, is—

- 10 10 An improved combined spade and pickax comprising in combination a shaft *a*, a metal tube *b* secured thereon, a spade *d* rotatable on a pivot *f*, supported in the bifurcated front end of the aforesaid metal tube *b*, a bolt *k*, a 15 pair of holes *i* for said bolt *k* in the tube *b*

corresponding in position to a bore in the head portion of the spade *d*, a movable guide-tube *g* on the tube *b* adapted to be fixed in regard to the shaft *a* to secure the position of the spade *d* as a pickax, and a slotted ring *e* 20 on the front end of the metal tube *b*, substantially as described and shown and for the purpose set forth.

In witness whereof I have hereunto signed my name, this 22d day of November, 1902, in 25 the presence of two subscribing witnesses.

CASPAR PRANGEMEIER.
